MINING MACHINE

Charles F. Osgood, Claremont, N. H., assignor to
 Sullivan Machinery Company, a corporation of
 Massachusetts

Application November 5, 1934, Serial No. 751,554

29 Claims. (Cl. 262—30)

This invention relates to mining machines, and more particularly to improvements in the feeding mechanism of a mining machine of the flexibly fed, continuous cutter, floor cutter type.

5 An object of this invention is to provide an improved mining machine feeding mechanism. Another object is to provide an improved feeding mechanism for a mining machine of the flexibly fed, continuous cutter, floor cutter type wherein relatively rotatable flexible member engaging feeding and guiding members are employed for feeding and guiding the machine and having improved means for independently driving said members through a wide range of feeding speeds. 10 A further object is to provide in a mining machine of the above character improved flexible feeding means wherein the feeding and guiding members may be driven either separately or simultaneously through a wide range of feeding speeds between zero and a predetermined maximum feeding speed. A further object is to provide a separate variable speed driving device for each feeding and guiding member whereby said members may be driven separately or simultaneously through a wide range of feeding speeds. Yet another object is to provide an improved driving means for the feeding and guiding members whereby the latter may be driven separately or simultaneously at either a relatively high speed or a relatively low speed, the low speed driving means including variable speed driving devices, one individual to each member, whereby said members may be driven through a wide range of low feeding speeds between zero and a predetermined maximum low speed. Still another object is to provide improved driving means for the feeding and guiding members whereby the latter may be independently driven through a wide range of low feeding speeds between zero and a predetermined maximum low speed including for each member an intermittent, frictional, variable speed driving device through which it, but not the other member, is driven. These and other objects and advantages of the invention will, however, hereinafter more fully appear.

In the accompanying drawings there is shown for purposes of illustration one form which the invention may assume in practice.

In these drawings,—

50 Fig. 1 is a horizontal sectional view, with parts shown in plan, of the illustrative embodiment of the improved feeding mechanism.

Fig. 2 is a central longitudinally extending vertical sectional view taken substantially on line 55 2—2 of Fig. 1.

Fig. 3 is a cross sectional view taken substantially on line 3—3 of Fig. 2.

Fig. 4 is an enlarged detail sectional view taken substantially on line 4—4 of Fig. 3.

Fig. 5 is an enlarged detail sectional view taken substantially on line 5—5 of Fig. 3.

In this illustrative construction the improved feeding mechanism is shown embodied in a mining machine of the flexibly fed, continuous cutter, floor cutter type particularly designed to use in room and pillar work, although it will be evident that the various features of the invention may be embodied in mining machines of other types.

The mining machine disclosed herein is of the same general character as that described in the patent to one Morris P. Holmes, Patent No. 1,875,335, granted September 6, 1932 and comprises a machine frame 1 of a low compact design having a plane bottom surface 2 adapted to rest upon and slide in any direction over the mine floor. 15 The machine is adapted to be propelled bodily over the mine floor and guided during such feeding movement by flexible feeding means including advance and receding flexible feeding and guiding elements 3 and 4 cooperating respectively, with relatively rotatable feeding and guiding members 5 and 6 herein preferably arranged in coaxial relation on transverse axes at the opposite sides of the machine frame in the manner shown in Fig. 1, the flexible feeding and guiding members herein being in the form of separate cables or ropes and the members 5 and 6 constituting haulage drums with which these cables respectively cooperate. In this particular instance, the cable 3 is wound on the drum 5 in a direction 20 opposite from that which the cable 4 is wound upon the drum 6, but as these drums are driven in opposite directions, the cables are both drawn by power. As described in the above mentioned Holmes patent, suitable guiding means are provided on the machine frame for guiding the feeding and guiding cables with respect to the haulage drums, and the feeding and guiding cables may be extended about these guiding means in various manners as is well understood by those 25 skilled in the art. Carried by the machine frame 1 is a motor 7 having its power shaft 8 horizontally disposed and extending longitudinally of the machine, and the haulage drums 5 and 6 may be driven by this power shaft through the 30 improved transmission connections, as herein-after described.

Now referring to the improved transmission means between the motor and the haulage drums 5 and 6, it will be noted that fixed to the motor 35

power shaft 8 is a spur pinion 10 driving through an intermediate gear 11 a spur gear 12 fixed to one end of a horizontal transmission shaft 13 herein extending longitudinally of the machine frame midway between the sides of the latter. The shaft 13 is suitably journaled in the machine frame 1 and has fixed thereto in longitudinally spaced relation thereon driving worms 14 and 15, the former constituting a fast speed driving worm and the latter constituting a low speed driving worm. The high speed worm 14 meshes with a high speed worm wheel 16 having its hub journaled in ball bearings 17, 17 suitably supported within bearing brackets 18, 18, suitably mounted within the machine frame. The low speed worm 15 meshes at its opposite sides with worm wheels 19 and 20 arranged on parallel vertical axes spaced equidistantly from and at opposite sides of the longitudinal center of the machine 20 and lying in a vertical plane extending transversely of the machine and parallel with a vertical plane including the haulage drum axes. As shown in Fig. 3, these worm wheels 19 and 20 are each connectible by low speed multiple disc 25 clutches 21, respectively, to parallel vertical shafts 22 and 23 suitably journaled at their upper and lower ends within the machine frame. Since the worm wheels 19 and 20 mesh with opposite sides of the worm 15, the shafts 22 and 23 are 30 rotated in opposite directions. Fixed to these shafts are worms 24 and 25, respectively, having teeth of the same lead and inclination and meshing with worm wheels 26 and 27, respectively. These worm wheels 26 and 27 are driven by the 35 worms 24 and 25 in opposite directions and are herein arranged in coaxial relation on axes alined with the axes of the haulage drums 5 and 6 and the fast speed worm wheel 16. These worm wheels 26 and 27 are each journaled on a bearing 40 28 and bearing sleeve 29 supported on cylindrical bearing supports 30 formed integral with and projecting inwardly from the vertical sides of the machine frame. Carried within the hub of the high speed worm wheel 16 is a bearing 31 in 45 which are journaled the adjacent ends of alined transmission shafts 32 and 33, the opposite ends of these shafts being journaled in bearings 34 supported within the sides of the machine frame. These shafts project laterally from the opposite 50 sides of the machine frame and have fixed thereto and support the haulage drums 5 and 6, respectively. Splined to the shafts 32 and 33 are sliding dental clutches 35 and 36 each having teeth engageable with teeth 37 formed on the adjacent 55 hub ends of the high speed worm 16 and teeth engageable with teeth 38 formed on the adjacent face of the low speed worm wheels 26 and 27, respectively. The operating means for these 60 clutches 35 and 36 comprise clutch shipper yokes 39 and 40, respectively, fixed to parallel longitudinally extending operating rods 41 and 42 suitably journaled within the top of the machine frame. Fixed to the outer ends of these operating rods are operating levers 43. It will 65 thus be seen that when the shafts 32, 33 are connected by the clutches 35 and 36 to the high speed worm wheel 16 the haulage drums 5 and 6 may be driven in winding direction at a relatively high speed, and when these shafts are connected 70 by the clutches 35 and 36 to the low speed worm wheels 26 and 27 the haulage drums may be driven in winding direction at a relatively low speed, it being possible by proper actuation of the 75 clutches 35 and 36 to drive the haulage drums in winding direction either separately or simul-

taneously at a relatively high speed or a relatively low speed.

Now referring to the improved mechanism for automatically operating the low speed clutches 21 to vary the driving speeds through the low speed gearing for each haulage drum, it will be noted that fixed to the transmission shaft 13 is a cam 45 herein having preferably four cam lobes, and engageable with this cam at the opposite sides thereof are spring loaded clutch applying and releasing devices generally designated 46 and 47, each having adjusting means whereby the time intervals of application and release of the low speed clutches will be varied at will. As these clutch operating and associated speed varying means for the low speed clutches are identical in design, a description of the operating mechanism 46 for the clutch 21 of the low speed drive for the haulage drum 5 will suffice for both. Engaging the cam 45 is an operating lever 50 fulcrumed 50 for pivotal movement at 51 on an adjustable eccentric 52 integral with an operating rod 53. This operating rod, as shown in Fig. 5, is rotatably mounted in bearing brackets 54, 54 suitably mounted within the machine frame, and 55 has fixed thereto at its outer extremity a control lever 55 having a suitable friction lock 56. By releasing the lock 56 the lever 55 may be swung to rotate the rod 53, and as a result swinging the eccentric 52 about the rod axis to 60 vary the location of the fulcrum point of the lever 50. The lever 50 is pivotally connected at 57 to a bifurcated element 58 (see Fig. 4) having formed thereon a cylindrical portion 59 and a reduced rod-like portion 60. The cylindrical portion 59 forms a shoulder 61. A spring 62 encircling the rod-like portion 60 is compressed between a collar 63 abutting an adjusting nut 64 threaded to the rod-like portion 60 and a collar 65 slidably mounted on the rod portion and normally engaging the shoulder 61. Slidably mounted on the cylindrical portion 59 is a sleeve-like portion 66 of a member 67 having side arms straddling the spring 62 and having a transverse portion 68 traversed by an opening 69 within 70 which the outer end of the rod-like portion 60 extends. The bifurcated end of the member 67 is pivotally connected at 70 to one arm of a bell crank lever 71 fixed to a shaft 72 suitably journaled in a bearing bracket 73 projecting inwardly from the adjacent side wall of the machine frame. The other arm of this bell crank is in the form of a yoke engaging the pressure plate 74 of the disc clutch 21. As above mentioned, the operating means for the low speed clutch of the low speed gearing for driving the haulage drum 6 is identical to that above described and includes adjusting means having an adjusting lever 75 similar to the operating lever 55 and having similar locking means 76. It will thus be seen that when the parts are in the position shown in Fig. 3 and the cam 45 is rotating, the cam lobes thereon periodically engaging the lever 50, when in the positions of Fig. 3, and like positions, effect swinging of the latter, thereby moving the rod 75 portion 60 axially towards the central vertical longitudinal plane of the machine frame, thereby increasing the tension of the springs 62 and, through these springs, the collars 65 and sleeve portions 66 of the elements 67, move the element 67 towards the central, longitudinal vertical plane of the machine, thereby swinging the levers 71 to apply intermittently the disc clutches 21. By adjusting the proper fulcrum eccentric 76 the position of the fulcrum of either lever 75

50 may be changed to vary the time intervals of application of the disc clutch. Also by certain adjustment of the fulcrum eccentric the lever fulcrum may be so adjusted that the lever 50 is at all times held against the surface of the cam, thereby effecting constant application of the disc clutch 21, the spring 62 compressing as the cam lobes engage and swing the lever. By moving the fulcrum eccentric to its extreme opposite position the cam may rotate while the disc clutch 21 is at all times released, the lever 50 swinging back and forth as the cam lobes engage the same without applying the clutch. It will thus be seen that the low speed gearing for the haulage drums 10 may be driven through the disc clutches at any desired low feeding speed between zero and a predetermined maximum low feeding speed, the gearing being driven intermittently through a wide range of low speeds and continuously at a maximum low speed. It will also be evident that when the disc clutches 21 are released and the high speed worm wheel 16 is connected to the drum drive shafts 32, 33 by the clutches 35 and 36 the haulage drums may be rotated in 20 winding direction at a relatively high machine moving or haulage speed; while when the operating means 46 and 47 are adjusted to effect application of the low speed clutches 21 and the shafts 32 and 33 are connected to the low speed worm wheels 26 and 27, the drums may be driven in winding direction at a relatively low feeding speed; and by varying the time intervals of application of the disc clutches 21 the haulage drums may be driven at any desired low feeding 30 speed between zero and a maximum low feeding speed. It will further be evident that when one or the other of the shafts is connected to the high speed worm wheel and the other shaft is connected to a low speed worm wheel, one haulage drum may be driven at a relatively high speed while the other haulage drum is simultaneously driven at a relatively low speed and that by independent adjustment of the clutch operating means 46 and 47 of the low speed clutches the low speed drives for the drums may be independently varied.

From the foregoing description the mode of operation of the improved feeding mechanism will be clearly apparent, and as the use of a room and pillar coal mining machine of the type disclosed is well understood by those skilled in the art, a detailed description of the mode of operation is considered unnecessary other than to state that the machine is fed over the mine floor by the feeding drum and is guided during such feeding movement by the guiding drum under the complete control of the operator through manipulation of the drum controlling clutches and the variable speed driving mechanism. By the provision of the wide range of low feeding speeds between zero and a predetermined maximum for each haulage drum, the feeding means is rendered extremely flexible, it being possible by suitable control of the drums to maneuver the machine in any desired manner. Other uses and advantages of the improved feeding mechanism will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine feeding mechanism, relatively rotatable feeding and guiding members adapted to cooperate respectively with flexible feeding and guiding means, and motor operated means for driving said members either separately or simultaneously through a wide range of low speeds between zero and a predetermined maximum including a separate variable speed transmission mechanism for each member, said transmission mechanisms including friction disc clutches, one individual to each member, and means common to both transmission mechanisms and driven by an element of the driving means for intermittently applying and releasing both of said clutches at timed intervals.

2. In a mining machine feeding mechanism, relatively rotatable feeding and guiding members adapted to cooperate respectively with flexible feeding and guiding means, and motor operated means for driving said members either separately or simultaneously through a wide range of low speeds between zero and a predetermined maximum including a separate variable speed transmission mechanism for each member, said transmission mechanisms including friction disc clutches, one individual to each member, means common to both transmission mechanisms and driven by an element of the driving means for intermittently applying and releasing both of said clutches at timed intervals, and associated means for varying the intervals of application and release of said clutches, said latter means being independently adjustable to vary independently the drive of said members.

3. In a mining machine feeding mechanism, relatively rotatable feeding and guiding members adapted to cooperate respectively with flexible feeding and guiding means, and motor operated means for driving said members either separately or simultaneously through a wide range of low speeds between zero and a predetermined maximum including a separate variable speed transmission mechanism for each member, said transmission mechanisms including friction disc clutches, one individual to each member, a cam driven by an element of the driving means, and clutch operating means actuated by said cam for intermittently applying and releasing said clutches at timed intervals.

4. In a mining machine feeding mechanism, relatively rotatable feeding and guiding members adapted to cooperate respectively with flexible feeding and guiding means, and motor operated means for driving said members either separately or simultaneously through a wide range of low speeds between zero and a predetermined maximum including a separate variable speed transmission mechanism for each member, said transmission mechanisms including friction disc clutches, one individual to each member, a cam driven by an element of the driving means, clutch operating means actuated by said cam for intermittently applying and releasing said clutches at timed intervals, and means associated with said clutch operating means for varying the intervals of application and release of said clutches, said latter means being independently adjustable to vary independently the drive of said members.

5. In a mining machine feeding mechanism, relatively rotatable feeding and guiding members adapted to cooperate respectively with flexible feeding and guiding means, and motor operated means for driving said members either separately

or simultaneously through a wide range of low intermittent speeds between zero and a predetermined maximum low speed and at a continuous maximum low speed including a variable speed transmission mechanism for each member through which it, but not the other member, is driven, each transmission mechanism including a variable speed intermittent and continuous transmission device and means common to both transmission mechanisms and driven by an element of the driving means for actuating said transmission devices.

6. In a mining machine feeding mechanism, relatively rotatable feeding and guiding members adapted to cooperate respectively with flexible feeding and guiding means, and motor operated means for driving said members either separately or simultaneously through a wide range of low speeds between zero and a predetermined maximum low speed including a variable speed transmission mechanism for each member through which it, but not the other member, is driven, said transmission mechanisms including friction disc clutches, one individual to each member and a cam driven by an element of the driving means for intermittently applying and releasing said clutches at timed intervals.

7. In a mining machine feeding mechanism, relatively rotatable feeding and guiding members adapted to cooperate respectively with flexible feeding and guiding means, and motor operated means for driving said members either separately or simultaneously through a wide range of low speeds between zero and a predetermined maximum low speed including a variable speed transmission mechanism for each member through which it, but not the other member, is driven, each of said transmission mechanisms including a clutch and means driven by an element of the driving means for intermittently applying and releasing said clutch at timed intervals and a cam common to the actuation of both clutch applying and releasing means.

8. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including driven elements, one in the drive for each member, and driving means for said driven elements including frictional control clutches, one for controlling the drive of each driven element, and mechanism actuated by an element of said driving means common to both clutches for automatically applying and releasing said clutches at timed intervals including yieldable clutch shipper mechanisms for said clutches respectively, said shipper mechanisms yieldable upon overload of said clutches to permit clutch slippage, and independently adjustable means adjustable at will during driving of said driven elements for increasing or decreasing the length of said intervals of application and release of said clutches to vary the driven speeds of said driven elements.

9. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including driven elements, one

in the drive for each member, and mechanism for driving said driven elements including a motor, and means for automatically intermittently connecting said driven elements independently in driving relation with said motor, said last mentioned means including a yieldable spring loaded connection for the automatic connecting means for each driven element and actuated by said motor through means common to both connecting means for automatically effecting such automatic connection at timed intervals, said yieldable connections adapted to yield upon overloading of said driven elements.

10. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including driven elements, one in the drive for each member, and driving means for said driven elements including driving elements arranged coaxially with and rotatable relative to said driven elements respectively, clutches for connecting said driven elements respectively in driving relation with said driving elements, and means for intermittently effecting and interrupting drive between said driving and driven elements including means for automatically intermittently applying and releasing said clutches, said clutch applying and releasing means including a cam member, pivoted clutch shipper members actuated by said cam member, one clutch shipper member for each clutch, and independently adjustable means adjustable at will during drive of said driven elements for altering the action of said cam member on said clutch shipper members, said adjustable means being independently adjustable for effecting independent variable speed drive of said driven elements.

11. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including driven elements, one in the drive for each member, and driving means for said driven elements including driving elements arranged coaxially with and rotatable relative to said driven elements respectively, clutches for connecting said driven elements respectively in driving relation with said driving elements, and means for intermittently effecting and interrupting drive between said driving and driven elements including means for automatically intermittently applying and releasing said clutches, said clutch applying and releasing means including a cam member, and clutch applying and releasing connections including pivoted clutch shipper members actuated by said cam member, one clutch shipper member for each of said clutches, said connections including spring loaded yieldable means between said cam member and the points on said shipper members of pressure application thereby adapted to yield upon overload of said clutches.

12. In a mining machine feeding mechanism, relatively rotatable feeding and guiding members adapted to cooperate respectively with flexible feeding and guiding means, and motor operated means for independently driving said members through a wide range of low intermittent

speeds between zero and a predetermined maximum low speed including driven elements, one in the drive for each member, and driving means for said driven elements including friction 5 clutches, one in the drive for each member, through which power is transmitted to effect drive of said driven elements, loading means for said clutches including an adjustable connection for each clutch, said connections embodying independent adjusting means adjustable at will 10 during driving of said driven elements, and means actuated by an element of said driving means common to both clutch loading means for actuating said connections for intermittently 15 loading said clutches to cause intermittent operation of said driven elements.

13. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including driven elements, 20 one in the drive for each member, and driving means for said driven elements including friction clutches, one in the drive for each driven element, and through which power is transmitted to effect drive of said driven elements, loading 25 means for said clutches including an adjustable connection for each clutch, motor driven means common to both clutch loading means for actuating said adjustable connections for intermittently loading said clutches 30 to cause intermittent operation of said driven elements, and means operable at will during driving of said driven elements for independently adjusting said connections to cause variable intermittent operation of said driven elements, 35 said latter means being independently adjustable to effect independent variable speed drive of said driven elements.

14. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including a driving element, 40 driven elements, one in the drive for each member, clutches for connecting said driven elements respectively in driving relation with said driving element, and means for intermittently applying and releasing said clutches at 45 timed intervals to effect intermittent drive of said driven elements including a continuously rotating cam means driven by said driving element, rods, one individual to each clutch, actuated by said cam means, and yieldable clutch loading means for each clutch, said yieldable clutch loading means actuated by said rods respectively, said clutch loading means adapted to yield upon overload of said clutches.

15. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including a driving element, 50 driven elements, one in the drive for each member, clutches for connecting said driven elements respectively in driving relation with said

driving element, and means for intermittently applying and releasing said clutches at timed intervals to effect intermittent drive of said driven elements including a continuously rotating cam means driven by said driving element, 5 rods, one individual to each clutch, actuated by said cam means, yieldable clutch loading means for each clutch, said yieldable clutch loading means actuated by said rods respectively, said clutch loading means adapted to yield upon 10 overload of said clutches, and independently adjustable means for respectively varying the intervals of application and release of said clutches to vary the driven speed of said driven elements, said adjustable means being independently adjustable whereby one of said driven elements may be driven at a speed relatively different from the driven speed of said other driven element.

16. In a mining machine feeding mechanism, 20 relatively rotatable feeding and guiding members adapted to cooperate respectively with flexible feeding and guiding means, and motor operated means for independently driving said members through a wide range of low intermittent speeds between zero and a predetermined maximum low speed including a driving element, 25 driven elements, one in the drive for each member, and driving connections between said driving and driven elements including frictional transmission devices, one in the drive for each driven element, and means actuated by an element of said driving connections for automatically intermittently loading and unloading said frictional transmission devices to effect intermittent variable speed drive of said driven elements, 30 said automatic means including a rotatable cam, elements actuated thereby, independently adjustable means for varying the engagement of said latter elements with said cam, 35 and yieldable means actuated by said last mentioned elements respectively, for yieldably imparting variable loading pressures to said frictional transmission devices.

17. In a mining machine feeding mechanism, 45 relatively rotatable feeding and guiding members adapted to cooperate respectively with flexible feeding and guiding means, and motor operated means for independently driving said members through a wide range of low intermittent speeds between zero and a predetermined maximum low speed including a driving element, 50 driven elements, one in the drive for each member, and driving connections between said driving and driven elements including friction clutches, 55 one clutch in the drive for each driven element, means actuated by a common element of said driving connections for automatically loading and unloading said clutches at predetermined timed intervals to effect intermittent drive of 60 said driven elements, said automatic clutch loading means including yielding clutch loading connections for said clutches respectively, through which the loading pressures of said loading means are yieldingly transmitted to said clutches, 65 and means for each clutch operable at will while said driving connections are in motion for varying the extent of the times of clutch loading, said latter means being independently adjustable to effect independent variable speed 70 drive of said driven elements.

18. In a mining machine feeding mechanism, relatively rotatable feeding and guiding members adapted to cooperate respectively with flexible feeding and guiding means, and motor op- 75

erated means for independently driving said members through a wide range of low intermittent speeds between zero and a predetermined maximum low speed including a driving element, 5 driven elements, one in the drive for each member, and driving connections between said driving and driven elements including frictional transmission devices, one device in the drive for each driven element, and means actuated by a 10 common element of said driving connections for automatically applying and releasing said frictional devices to effect intermittent variable speed drive of said driven elements including spring loaded actuating members through which 15 the clutch loading pressures are variably transmitted to said frictional devices, and independently adjustable means for varying the tension of the springs of said actuating members, said frictional devices being applied through said actuating members by the springs thereof.

19. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed or at a continuous maximum low speed including a driving element, 25 driven elements, one in the drive for each member, and driving connections between said driving and driven elements including friction clutches, one clutch in the drive for each driven element, and for loading said friction clutches 30 for applying different loading pressures to the clutches including means acting automatically during the operation of the driving connections and including an actuating element common to both clutch loading means for intermittently relieving the loading pressures applied to the 35 clutches to provide for variable operation of the driven elements, said clutch loading means embodying means for applying loading pressures such that even when the loading pressures are 40 reduced by said automatically acting means the clutches are held applied to provide for continuous operation of the driven elements.

20. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including a driving element, 50 driven elements, one in the drive for each member, driving connections between said driving and driven elements including friction clutches, one in the drive for each driven element, and means for loading the friction clutches for applying different loading pressures to the clutches including means acting automatically during the operation of the driving connections and including an actuating element common to both clutch 55 loading means for intermittently relieving the loading pressures applied to the clutches to provide for variable operation of the driven elements, said clutch loading means including resilient elements for said clutches respectively, and means for variably tensioning the same, and said 60 automatically acting means embodying means to relieve intermittently the tension of said resilient elements.

21. In a mining machine feeding mechanism, relatively rotatable feeding and guiding mem-

bers adapted to cooperate respectively with flexible feeding and guiding means, and motor operated means for independently driving said members through a wide range of low intermittent speeds between zero and a predetermined maximum low speed including a driving element, 5 driven elements, one in the drive for each member, and driving connections between said driving and driven elements including friction clutches, one in the drive for each driven element, and means for loading said friction clutches for applying different loading pressures to the clutches, said last mentioned means including means acting automatically during the operation of the driving connections for intermittently relieving the loading pressures applied to the clutches to provide for variable operation of the driven elements, said clutch loading means including resilient elements for said clutches respectively, means for variably tensioning the same, and said automatically acting means embodying means to relieve intermittently the tension of said resilient elements, elements adapted to be manually adjusted to determine the tensioning of said resilient elements, and means common to both clutch loading means for intermittently causing said adjustable elements to relieve the tension of said resilient elements.

22. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including a driving element, 30 driven elements, one in the drive for each member, and driving connections between said driving and driven elements including friction clutches, one clutch in the drive for each driven element, and means for loading the friction clutches for applying different loading pressures to the clutches, said last mentioned means including means acting automatically during the 35 operation of the driving connections for intermittently relieving the loading pressures applied to the clutches to provide for variable operation of the driven elements, said clutch loading means including resilient elements for said clutches respectively, means for variably tensioning said resilient elements, said automatically acting means embodying means to relieve intermittently the tension of said resilient elements, said resilient element tensioning means being 40 tensioned by means of levers respectively connected thereto, manual means provided for shifting the fulcrums of said levers to vary the tensioning of said resilient elements, and means for intermittently actuating said levers operative 45 periodically to relieve the tension of said resilient elements and comprising rotatable cam means common to both.

23. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined 50 maximum low speed or at a continuous maximum low speed including a driving element, driven elements, one in the drive for each member, driving connections between said driven elements respectively, and said driving element in- 55

cluding friction clutches, one in the drive for each driven element, loading means for said clutches respectively including a yielding connection for each clutch through which the clutch 5 loading pressures are yieldingly transmitted to effect loading of said clutches, and means actuated by a common element of said driving connections for selectively intermittently or continuously tensioning said yielding clutch loading 10 connections to load said clutches to an extent sufficient to effect selective intermittent or continuous drive of said driven elements.

24. In a mining machine feeding mechanism, relatively rotatable feeding and guiding members 15 adapted to cooperate respectively with flexible feeding and guiding means, and motor operated means for independently driving said members through a wide range of low intermittent speeds between zero and a predetermined maximum low speed or at a continuous maximum low speed including driving elements, driven elements, one in the drive for each member, friction clutches, one 20 maximum low speed including a driving element, driven elements, one in the drive for each member, and driving connections between said driving and driven elements including friction clutches, one in the drive for each driven element, loading means for said clutches including 25 yielding connections for said clutches respectively through which the clutch loading pressures are yieldingly transmitted to effect variable drive of said driven elements including a cam, levers arranged for actuation by said cam and operatively connected to said yielding clutch loading connections respectively, and independently adjustable means for independently shifting the fulcrums of said levers to vary the range of actuation 30 thereof.

25. In a mining machine feeding mechanism, relatively rotatable feeding and guiding members adapted to cooperate respectively with flexible feeding and guiding means, and motor operated 40 means for independently driving said members through a wide range of low intermittent speeds between zero and a predetermined maximum or at a constant maximum low speed including a driving element, driven elements, one in the drive for each member, and driving connections between said driving and driven elements including friction clutches, one in the drive for each driven element, loading means for said clutches including 45 yielding connections for said clutches respectively through which the clutch loading pressures are yieldingly transmitted to effect clutch loading, and means for variably tensioning said yielding clutch loading connections variably to load said clutches to effect variable drive of said driven 50 elements including a cam, levers arranged for actuation by said cam and operatively connected to said yielding clutch loading connections respectively, and independently adjustable means for shifting the fulcrums of said levers to vary 55 independently the range of actuation thereof, said shifting means including means providing a range of adjustment permitting constant tensioning of said yielding connections.

26. In a mining machine feeding mechanism, 65 relatively rotatable feeding and guiding members adapted to cooperate respectively with flexible feeding and guiding means, and motor operated means for independently driving said members through a wide range of low intermittent speeds 70 including a driving element, driven elements, one in the drive for each member, and driving connections between said driven and driving elements including friction clutches, one clutch in the drive for each driven element, loading means 75 for said clutches respectively, each including the

yielding clutch loading spring connection through which the clutch loading pressure is transmitted to effect clutch loading, and independently adjustable means for selectively intermittently or continuously tensioning said yielding clutch loading connections to load said clutches to an extent sufficient to effect selective intermittent or continuous drive of said driven elements, said latter means including actuating means common to both clutch loading connections.

27. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed or at a continuous maximum low speed including driving elements, driven elements, one in the drive for each member, friction clutches, one clutch in the drive for each driven element, each friction clutch comprising elements fixed as regards relative rotation with respect to said driving and driven elements respectively, and means operative to provide non-slip engagement between said clutch elements during no part of each complete revolution of the clutch elements which are fixed relative to the driving elements, during a selective fraction of each revolution of said clutch elements, or during a complete revolution of said clutch elements, selectively at will, including spring-loaded elements, one for each clutch, clutch loading elements engageable by the latter elements and operative when adequately pressed by the latter elements to effect clutch loading, means common to both clutches for actuating said clutch loading elements, and means for providing for such non-slip engagement throughout any desired portion of a revolution of the clutch elements fixed as regards rotation with respect to 30 said driving elements.

28. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including driving elements, driven elements, one in the drive for each member, friction clutches for connecting said driven elements in driving relation with said driving elements respectively, and means for intermittently variably applying and releasing said clutches to effect intermittent variable speed drive of said driven elements including a cam having a face of fixed contour, yieldable clutch applying connections, and means engageable with the cam face for actuating said yieldable clutch applying connections and embodying independently adjustable means for varying the range of actuation of said yieldable connections to vary the intervals of application and release of said clutches.

29. In a mining machine feeding mechanism, relatively rotatable feeding and guiding members adapted to cooperate respectively with flexible feeding and guiding means, and motor operated means for independently driving said members through a wide range of low intermittent speeds between zero and a predetermined maximum low speed including driving elements, driven elements, one in the drive for each member, friction clutches for connecting said driven elements in driving relation with said driving elements respectively, and means for intermittently variably

applying and releasing said clutches to effect intermittent variable speed drive of said driven elements including a cam having a face of fixed contour, yieldable clutch applying connections, and means engageable with the cam face for actuating said yieldable clutch applying connec-

tions and embodying independently adjustable means operable at will while said driving elements are in motion for varying the range of actuation of said yieldable connections to vary the intervals of application and release of said clutches.

CHARLES F. OSGOOD.

CERTIFICATE OF CORRECTION.

Patent No. 2,062,662.

December 1, 1936.

CHARLES F. OSGOOD.

It is hereby certified that error appears in the printed specification of the above numbered patent requiring correction as follows: Page 6, first column, line 34, claim 19, after the word "and" insert means; and that the said Letters Patent should be read with this correction therein that the same may conform to the record of the case in the Patent Office.

Signed and sealed this 5th day of October, A. D. 1937.

Henry Van Arsdale

(Seal)

Acting Commissioner of Patents.
